(57) **CLAIM**

I claim the ornamental design for a interchangeable reconfigurable protective padded panel, as shown and described.

DESCRIPTION

FIG. 1 is an exploded perspective view of an interchangeable reconfigurable protective padded panel, showing my new design;

FIG. 2 is an assembled front perspective view thereof;

FIG. 3 is a front elevational view of FIG. 2;

FIG. 4 is a top plan view thereof in an alternate configuration;

FIG. 5 is a bottom plan view of FIG. 4;

FIG. 6 is a right-side elevational view of FIG. 4; the left-side elevational view being a mirror image thereof;

FIG. 7 is a front elevational view of FIG. 4; and,

FIG. 8 is a rear elevational view of FIG. 4.

The interchangeable reconfigurable protective padded panel is shown in alternate configurations for ease of illustration.
